(57) **CLAIM**

The ornamental design for a stylus pen clip, as shown and described.

DESCRIPTION

FIG. 1 is a front bottom side perspective view of the stylus pen clip showing my new design;

FIG. 2 is a front elevational view thereof;

FIG. 3 is a right side view thereof which is a mirror image of the left side thereof;

FIG. 4 is a back elevational view thereof;

FIG. 5 is a bottom plan view thereof; and,

FIG. 6 is a top plan view thereof.

The broken lines in all figures showing other portions of the pen and the face of the circular feature on the clip are included to show environmental structure only and form no part of the claimed design.
